Primary Examiner — Katherine Glennon*Assistant Examiner* — Yuan Yuan*(74) Attorney, Agent, or Firm* — Rumit Ranjit Kanakia**(57) CLAIM**

The ornamental design for a dancing lion toy, as shown and described.

DESCRIPTION

FIG. 1 is a perspective view of a dancing lion toy showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top plan view thereof; and,

FIG. 8 is a bottom plan view thereof.

The broken lines in the figures are for the purposes of illustrating portions of the dancing lion toy, which form no part of the claimed design.
